United States Patent Office

Des. 198,045
Patented Apr. 21, 1964

198,045

TIME PUNCH OR SIMILAR ARTICLE

John J. Brett, Cleveland, Ohio, and Albert Hohmann,
Brooklyn, N.Y., assignors, by mesne assignments, to
Consolidated Dynamics Corporation, Brooklyn, N.Y.,
a corporation of New York

Filed June 18, 1963, Ser. No. 75,405

Term of patent 14 years

(Cl. D42—7)

FIG. 1

Des 198,045

PAGE 2

FIG. 2

FIG. 3

FIG. 4

FIG. 5

FIGURE 1 is a top plan view of a time punch showing our new design;

FIGURE 2 is a front elevational view thereof;

FIGURE 3 is a right-side elevational view thereof;

FIGURE 4 is a left-side elevational view thereof; and

FIGURE 5 is a rear elevational view thereof.

We claim:

The ornamental design for a time punch or similar article, substantially as shown.
